UNITED STATES PATENT OFFICE

ANDREW F. WOOD, OF JERSEY CITY, NEW JERSEY

LOUD-SPEAKER DEVICE

Application filed June 21, 1927. Serial No. 200,379.

This invention relates particularly to a loud speaker or loud speaking telephone of the type in which sound is propagated from a vibrating surface directly to the free air without the intervention of a horn, the usual cone type loud speaker being an example of this type of apparatus. Nevertheless, certain features of my conical diaphragm and the conical actuating means for transmitting motion to such diaphragm are applicable to any form of sound reproducer employing a vibrating diaphragm, either with or without a horn, and actuated by any source of vibrating energy, mechanical, electric or electromagnetic.

The object of the present invention is to provide a sound reproducing device which, to a high degree, faithfully reproduces a comparatively wide range of audible frequencies.

A further object of the invention is to provide a loud speaker device, which, for a given energy input, delivers an increased volume of sound.

The invention further contemplates in combination with a cone type diaphragm, a sounding board, against which the diaphragm actuating mechanism preferably rests, so that the reaction from the forces against the diaphragm will act upon said sounding board, and in the preferred construction the invention provides a second sounding board spaced apart from said first-mentioned sounding board to provide a resonant air space therebetween.

Another object of the invention is to provide a conical actuating element through which vibration is transmitted to a larger conical diaphragm at points removed from the apex of the latter.

The present invention aims to increase the efficiency of the cone type loud speaker by the combination of two conical or dished diaphragms of somewhat different conical angles, whereby, although the members be connected together at a point, there will, nevertheless, be provided between them an air space, the volume of which expands radially outward.

Another object is to provide a conical or

dished diaphragm, the marginal or basal edges of which are so shaped as to provide a plurality of areas which are not fully supported by the central conical area but extend therefrom, said areas therefore, being more flexible than if they were connected by portions of the general conical surface.

Further objects of the invention will be apparent from the following description, in which reference is had to the accompanying drawings, in which:

Figure 1 is an axial cross-section of a loud speaker device having a double conical diaphragm and a conical actuating means for said diaphragm.

Fig. 2 is a plan view of the loud speaker shown in Fig. 1.

Fig. 3 is a plan view of a loud speaker similar in construction to the device shown in Figs. 1 and 2, except that the diaphragms and sounding boards are circular instead of star-shaped.

Figs. 4 and 5 are respectively a plan view and central vertical cross-section of a modified form of loud speaker having a dished diaphragm.

Figs. 6, 7 and 8 are plan views of diaphragms according to the present invention having different marginal contours.

Fig. 9 is an axial cross-section of a phonograph reproducer employing a conical diaphragm actuated through a smaller conical diaphragm.

Fig. 10 shows a telephone receiver having a conical diaphragm-actuating element.

Referring to the embodiment shown in Figs. 1 and 2, the loud speaking device comprises two relatively large conical diaphragms 1, 2 connected together at their apexes 3. These diaphragms, while having a substantially conical contour, are star-shaped so as to provide areas 4, 4' which extend beyond the central conical surface and are therefore much more flexible than if their outer portions were connected together by a surface, which, so to speak, made them an integral part of a general conical surface such as would be represented by a circular cone. A portion of such an imaginary cone is indicated in dotted lines in Fig. 2. It will be

understood that these flexible portions comprising the points of the star-shaped diaphragms are not flat, but to a considerable degree partake of the conical contour of the central portion of the diaphragm because they form a part of and extend therefrom. This is desirable, because while a certain degree of flexibility in these areas greatly improves the quality of reproduction, nevertheless they must have a certain strength or rigidity in order to efficiently propagate sound.

The diaphragms 1, 2 are actuated by any suitable electromagnetic unit 5, the vibrating stem 6 of which is attached to the conical diaphragm actuator 7. This conical actuator is preferably formed of the same material as the conical diaphragms themselves, and this material may be of any suitable nature. The material of the diaphragms forms no part of the present invention and may comprise any fibrous substance, such as paper, parchment or very light wood, or the diaphragms may be made of thin aluminum sheets. In fact, any material that is light and relatively strong may be employed. The best results have been obtained with stiff paper.

The conical actuator 7 which is connected to the vibrating member of the electromagnetic unit, is in itself a conical diaphragm, its basal edges being preferably flanged to provide an annulus 8 which is cemented to the inner or concave face of diaphragm 1. This arrangement provides an enclosed air space 9 between the actuator and the diaphragm 1 which is believed to contribute a desirable resonance effect. An important advantage of this arrangement, however, is had through the application of the vibrating energy to the major diaphragm 1 at points removed from the apex thereof. The direct mechanical vibration from the electromagnetic unit is transmitted through the conical actuator 7 to the major diaphragm 1 and acts directly upon such diaphragm through the annular connection 8. This arrangement results in a more positive and effective action of the unit upon the diaphragm 1, so that the reproduced sound corresponds more closely to the applied vibrations than in diaphragms where such vibrations are applied at a single central point on the diaphragm.

Furthermore, the opposite disposition of the conical diaphragm and its conical actuator provides the additional advantage that when the actuator is moving to the left, and consequently having its maximum rigidity through the inherent self-supporting effect of a conical surface, the diaphragm which it actuates, because of its opposite conicity, is least rigid. On the reverse movement, the major diaphragm 1 is the more rigid and the conical actuator less rigid because it does not receive the inherent bracing effect of a conical sheet being stressed to flatten or expand

it, and thus a compensation is had which tends to render the opposing phases of any complete wave movement similar. The conical bracing effect referred to is due to the fact that in order to expand or flatten a cone made of sheet material, it is necessary to deform such material by stretching it or rupturing it, whereas a force tending to contract or collapse the cone need only slightly bend it, as in a series of radial flutes for example, to destroy to a considerable extent its rigidity with respect to such force. For example, a parasol not latched in the open position will be found to strongly resist a force tending to open or flatten it beyond a certain point determined by its design. Nevertheless, a very slight force acting in the opposite direction will cause the collapse or folding up of the parasol.

The electromagnetic unit is preferably mounted directly upon the face of a sounding board 15 so that the mechanical reaction of vibrating the conical diaphragms is transmitted to such sounding board. This sounding board may be of spruce or other suitable resonant material, and should be somewhat larger than the largest of the diaphragms mounted in front of it. The sounding board effect is further increased by mounting to the rear (or to the left, as shown in Fig. 1) of the sounding board 15, a second sounding board 16, the two being spaced apart to provide a resonating chamber 17, as shown. The boards are connected together near their edges by pins 18, and when two sounding boards are employed, the one nearest the diaphragms is preferably fenestrated to provide openings 19 through which sound waves from the rear of the diaphragms may pass directly to the resonance chamber 17. The device is provided with a hanger bracket 20 mounted on the rear of the sounding board 16, so that it may be hung against the wall, and this bracket, together with the small fittings 21, serve to hold the sounding board out of contact with the wall so that it is free to vibrate over the greater part of its central area. The loud speaker device may, of course, be mounted upon a pedestal. This pedestal comprises a weighted base 23 having an upright column 24, which is threaded into a socket 25 concealed between the two sounding boards. If it is desired to hang the loud speaker against the wall, the pedestal is thus readily removed.

In certain types of electromagnetic units for loud speaker diaphragms the actuating pin 6 is sufficiently rigid to permit of the mounting of one or more diaphragms thereon, the diaphragms being supported solely by such pin. Where multiple diaphragms are to be employed, however, it is preferable to provide other means of support, and such support should be designed to provide the utmost freedom of movement for the dia-

phragm. To this end, according to the present invention, the multiple diaphragm arrangement illustrated in Figure 1 is suspended upon a wire or other flexible member 26 from a bar 27 extending forwardly from the sounding board 15. The flexible strand is preferably attached to the inner diaphragm 1, as by means of a rivet 28 at a point immediately above the center of gravity of the connected cones 1, 2 and 7. By this arrangement the actuating pin 6 is entirely relieved of the duty of supporting any part of the weight of the cones. The suspending wire may be adjustably secured to the rod or post 27 by means of a set screw 28' which clamps the wire in any desired adjustment, the wire sliding free through the vertical bore 28" when the said screw is loosened.

In the preferred construction, rod 27 extends through the two sounding boards 15, 16, thus providing in a single element the spacing post 18 which maintains the sounding boards in proper relationship and also the support for the diaphragms. The portion 18 of the rod 27 which lies between the two sounding boards is somewhat enlarged to provide shoulders against which the sounding boards are clamped. The rod is threaded at either side of such enlarged portion, and the left-hand sounding board (Fig. 1) is clamped in place by a nut 29; the right-hand sounding board is held in place by means of the fitting 20 which is threaded onto the end of the rod, the said fitting providing the eye or other suitable means for hanging the loud speaker against the wall.

In Fig. 3 there is illustrated a loud speaker similar in every respect to the embodiment illustrated in Figs. 1 and 2, except that the diaphragms 1 and 2, and also the sounding boards 15, 16, are round instead of star-shaped, such diaphragms therefore, being of the conventional cone type. While with such an arrangement the advantages due to the salient areas 4 and 4' of the star-shaped diaphragm are not had, nevertheless, the application of a conical actuator to a cone diaphragm of the usual type effects an improvement in the quality of reproduction in such loud speakers.

The combination of two conical diaphragms, the surfaces of which are inclined at different angles but in the same angular sense from a transverse plane, will be found to favorably affect the quality of reproduction. While in the preferred construction the cones are directly connected together at their apexes, very satisfactory results can be had by combining two cones of similar shape and spacing them apart to provide an air chamber between them, the only absolute requirement as to the disposition of the cones being that their surfaces slope in the same sense, though not necessarily in the same

degree, from a plane transverse to the conical axis,—that is to say—the one cone, at least in part, projects within the second cone instead of the cones being arranged in opposition one to another as has hitherto characterized certain types of double cone loud speakers. It is not essential that the superposed surfaces of the two cones diverge in the radial direction in order to provide an expanding tone chamber between them, because the volume of an annulus between the two cones at different radii will increase according to the squares of such radii, even though the cones be of similar taper or conical angle. Nevertheless, it is preferred to make the conical angle of the inner cone 1 somewhat more acute than that of the outer cone 2 so that a still further radial expansion is permitted.

In Figs. 4 to 8 inclusive are illustrated loud speaker devices according to the present invention, in which the principle of employing a conical or dished diaphragm having salients of various forms extending from the central conical or dished portion is shown. The device illustrated in Figs. 4 and 5 comprises a dished diaphragm 30 which is shield-shaped, the flexible salients being provided at the points 31 and 32. The diaphragm is directly actuated by the electromagnetic unit 33 at a point 34, which coincides with what may be termed the axis of generation of the somewhat spherical form of the surface. In this modification the actual form of the diaphragm surface is that of a cone, the apex of which has been rounded off, as indicated in Fig. 3. A dished diaphragm of this contour may be readily formed by radially slitting a conical diaphragm towards its center and then pressing the segments thus formed into the desired rounded contour. This operation will cause the margins of the segments to overlap, and these overlapping margins 35 are cemented together. If a ductile material is used for the diaphragm, it may, of course, be pressed or drawn into the dished form without cutting. The loud speaker unit 33 in this construction is mounted directly upon a sounding board 37 in the manner hereinbefore described. In the present instance only a single sounding board is employed, this board being provided with a hanger ring 39 and posts 40, by means of which the sounding board, when hung against a wall, is held away therefrom to permit its free vibration and also to afford a resonant air space between itself and the wall. The diaphragm shown in Fig. 6 is a further modification in which salients 42, of greater flexibility, are formed by shaping the marginal edges of the conical surface to provide relatively narrow projecting areas bounded by four similar arcs 43.

The diaphragm 45 illustrated in Fig. 7 provides in still another form flexible salients 46,

47 and 48, the three types of salients each differing from the other, so that the symmetry of the diaphragm with respect to a horizontal transverse axis, is destroyed. This characteristic is also present in the device illustrated in Figs. 4 and 5 and results in a tendency to eliminate objectionable periodic 70 effects of the diaphragm.

5 The diaphragm illustrated in Fig. 8 is more 10 properly described as pyramidal than conical, and its apex is asymmetrically disposed with respect to any possible axis that may be chosen. The basal edge of the diaphragm forms substantially a rectangle, the corner 15 areas of which provide flexible salients 50, 51, 52 and 53, which extend outward beyond the central pyramidal portion.

19 In Fig. 9 there is illustrated a phonograph 20 reproducer employing a diaphragm 60, which is acted upon by a conical actuator 61, according to the present invention. Mechanical vibrations are transmitted from the surface of the record through a stylus bar 62 in the usual manner, but this stylus bar, instead of being 25 attached directly to the diaphragm 60, is connected to the apex 63 of the conical actuator 61. The diaphragm 60 is of conical form and may be made of thin aluminum sheet, the 30 conical actuator being formed of the same material and having an annular flange 64 which is connected to the diaphragm. The inner surface 65 of the reproducer head 66 conforms to the conical surface of diaphragm 60 but is spaced apart therefrom in accordance with usual practice, to provide a passage 35 65' therebetween for the sound energy which ultimately passes out through the throat 67 to the phonograph horn (not shown). Also, in accordance with general practice, the diaphragm is flexibly mounted at its outer edge in a resilient gasket 68.

40 The adaptation of the conical actuator to a telephone receiver diaphragm is illustrated in Fig. 10. In this construction a flat diaphragm 70, preferably formed of mica, is employed. Cemented to the rear of this diaphragm is an actuating cone 71, which may be made of parchment. The apex of this cone 45 is flattened to receive an iron armature 72, which is acted upon by the telephone electromagnets 73. Diaphragm 70 is flexibly mounted at its edges between suitable gaskets 74. A telephone receiver of this type is very sensitive. The mica diaphragm can be made relatively thin because it is greatly strengthened by the parchment cone 71, and the total 50 vibrating mass of the diaphragm and actuating cone will be materially less than that of the usual iron diaphragm employed in telephone receivers. It will be seen that the principle of imparting vibrating energy to the 55 larger diaphragm through the actuating cone, about an annulus removed to a considerable extent from the center of such diaphragm, corresponds to the underlying principle of

the loud speaker device illustrated in Figs. 1 and 2, but while small diaphragms such as are employed in telephone receivers, give very good results when made flat, in the large diaphragms necessarily employed in loud speakers, where such diaphragms act directly upon unconfined air, the conical form of diaphragm is to be preferred.

70 While various embodiments and modifications of my invention have been hereinbefore described and illustrated, it is to be understood that these are merely illustrative and that the invention may be otherwise variously modified and embodied without departing 75 from the spirit thereof, as set forth in the 80 following claims.

What I claim is:

1. A sound reproducer comprising a substantially conical main diaphragm, a smaller opposed actuator diaphragm basally connected thereto in such manner as to provide a substantially enclosed air chamber therebetween, and actuating means adapted to apply vibrations to said diaphragm through said actuator diaphragm, said main diaphragm having a total area at least twice as great as the area of said actuator diaphragm.

85 2. A sound reproducer comprising a substantially conical diaphragm and a hollow conical actuator element adapted to transmit vibrations thereto, said conical element engaging said diaphragm in an annulus around the diaphragm apex, the diameter of said annulus being materially less than the diameter of the diaphragm, and the said diaphragm and actuator element constituting the walls of a substantially closed air chamber therebetween.

90 3. A loud speaker having a plurality of co-axially disposed interfitting conical diaphragms, the apex portions of which are connected together, the inner diaphragm being more sharply tapered than the diaphragm surrounding it whereby a radially outward 95 expanding air chamber is provided between 100 them, and actuating means for vibrating said diaphragms.

105 4. A loud speaker according to claim 3, further characterized in that said actuating means comprises a smaller and opposed conical actuating diaphragm substantially co-axial with said first-mentioned diaphragms, and connected to the concave face of said inner diaphragm, and an actuating unit connected near the apex of said actuating diaphragm and adapted to apply vibration to the latter.

110 5. A loud speaker according to claim 3, further characterized in that the said diaphragms are mounted in front of a sounding board and spaced apart therefrom to permit the free egress of sound between said diaphragms and said board.

115 6. A loud speaker according to claim 3, further characterized in that the said dia- 120 phragms

phragms are mounted in front of a sounding board with the basal portion of the outer diaphragm appreaching the said sounding board but being separated therefrom to permit the free egress of sound between said diaphragms and said board, an actuating unit mounted on said sounding board, and connected to the smaller conical diaphragm lying within the larger diaphragm, whereby the vibrations produced by said unit are transmitted to the larger diaphragm through the smaller one.

7. A loud speaker according to claim 3, further characterized in that at least one of said diaphragms is shaped to provide salient areas extending materially beyond the central conical area, a sounding board spaced apart from the basal portion of the said diaphragms, an actuating unit mounted on said sounding board and an opposed conical actuating diaphragm fastened on the concave face of said inner diaphragm and adapted to transmit vibrations from said unit to said inner diaphragm.

8. A loud speaker comprising a conical diaphragm, a substantially flat sounding board, means to actuate said diaphragm, said means being mounted directly against said sounding board, the said conical diaphragm being disposed with its basal edge adjacent to but separated from the said sounding board, the apex of said diaphragm being directed away from said board.

9. A loud speaker according to claim 8, further characterized in that a second substantially flat sounding board is mounted to the rear of the said first-mentioned sounding board whereby to provide a sound chamber therebetween, said chamber permitting free egress of sound parallel to the plane of the sounding boards.

40 10. A loud speaker according to claim 8, further characterized in that spacing means are provided to hold the main area of the sounding board away from a wall surface against which it may be hung, whereby to permit free vibration of the board over the greater part of its area and free egress of sound from between the rear of the board and the wall against which it may be mounted.

50 11. A sound reproducer comprising a diaphragm having a central concave and substantially smooth portion and a plurality of salients projecting from said central portion, said salients forming continuations of the sloping surfaces of said central portions and providing diaphragm surfaces of substantial area which are more flexible than if they were included in the continuous central area of the diaphragm, and actuating means engaging said central portion to vibrate said diaphragm.

60 12. A sound reproducer according to claim 11, further characterized in that the said actuating means for vibrating said diaphragm is adapted also to provide the required dia-

phragm support, whereby the outer portions of the said diaphragm salients are permitted free and unobstructed movement.

13. A loud speaker comprising a vibrating diaphragm having a substantially smooth conical contour, the basal part of said conical diaphragm having a plurality of outer portions at a distance from the apex of the cone, the edge of the said conical diaphragm being formed so as to connect said portions by lines which approach the apex of the diaphragm at points between said outer portions, whereby the said outer portions are rendered relatively flexible as compared with the central portion of the diaphragm.

75 14. A loud speaker comprising a vibrating diaphragm having a substantially conical contour, the basal part of said conical diaphragm having a plurality of outer portions of substantial area, the edge of the cone being formed so as to connect said portions by lines which approach the apex of the cone at least as near as would straight lines connecting said outer portions, whereby the said outer portions are rendered relatively flexible as compared with the central portion of the diaphragm.

80 15. A loud speaker comprising a concave diaphragm, the surface of which slopes on all sides from an apex to a surrounding basal edge, the basal part of said diaphragm having relatively flexible outer portions of substantial area, the said basal edge being formed so as to connect said outer portions by marginal lines which have a maximum approach to the said apex at least as great as would straight lines connecting said outer portions, and means to centrally vibrate said diaphragm.

85 16. A loud speaker comprising a vibrating diaphragm, said diaphragm having a substantially smooth conical contour, the basal edge of said conical diaphragm having a plurality of symmetrically-arranged terminal points, said basal edge connecting said terminal points by lines which approach the apex of said conical diaphragm a sufficient distance at points intermediate said terminal points to provide the diaphragm with a plurality of salient portions of substantial area which are materially more flexible and easier to vibrate than if they mutually formed a part of a continuous conical surface.

90 In witness whereof, I have hereunto signed my name.

100 ANDREW F. WOOD.
